UNITED STATES PATENT OFFICE.

JOACCHIM JOHANNES DAHL, OF HAMBURG, GERMANY.

TOOL-HOLDER FOR METAL-WORKING MACHINES.

SPECIFICATION forming part of Letters Patent No. 617,008, dated January 3, 1899.

Application filed May 4, 1898. Serial No. 679,738. (No model.)

To all whom it may concern:

Be it known that I, JOACHIM JOHANNES DAHL, a subject of the German Emperor, and a resident of Hamburg, in the German Empire, have invented certain new and useful Improvements in Tool-Holders for Metal-Working Machines, of which the following is a specification.

This invention relates to tool-holders for metal-working machines, and particularly for planing-machines, which are so arranged that the tool is held in a separate sleeve or lining mounted in a reversible socket of the tool-holder proper fixed to the slide-head of the machine. The said socket is automatically shifted or turned through an angle of one hundred and eighty degrees at the end of each stroke in well-known manner. In this reversible socket the sleeve or lining holding the tool is capable of being adjusted in position during the working of the machine—that is to say, the backward and forward movement of the work.

The invention is illustrated in the accompanying drawings, which illustrate one practical form of construction, and in which—

Figure 1 shows a front view of a metal-planing machine with a tool-holder made in accordance with this invention. Fig. 2 shows a front view of the tool-holder, drawn to a larger scale. Fig. 3 shows a similar view of the tool-holder, but partly in section, the cutting-tool and the socket containing it being turned through an angle of one hundred and eighty degrees. Fig. 4 is a vertical section on line 4-4, Fig. 2. Figs. 5 and 6 are horizontal sections on lines 5-5 and 6-6 of Figs. 2 and 3, respectively.

Similar letters of reference indicate corresponding parts in all the figures of the drawings.

The casing *a*, forming the tool-holder proper, is arranged on a horizontal pivot *a'* on the slide-head *A* of the planing-machine and is adapted to be fixed by clamping-screws *a*³, arranged in the slots *a*². Within this casing *a* is a socket *b*, which is held by nuts *b*¹ and *b*², the upper end of the said socket being provided with a toothed wheel *b*³ and the lower end with two diametrically-arranged notches or grooves *b*⁴. The socket *b*, which is rotatable

in the casing *a*, is secured in one or the other of its extreme positions by a spring-bolt *c*, which fits into the grooves *b*⁴, the said bolt being suitably arranged in a projection 55 on the casing *a* and connected with a coupling-lever *c'*, pivoted at *c*² to the casing *a*. The central opening of the socket *b* is widened at the lower part for the purpose of receiving a sleeve *d*, likewise provided with a central 60 aperture. As shown in Figs. 2, 3, and 4, the sleeve *d* has at its lower end an enlarged vertically-slotted head, forming a shoulder or abutment that has bearing on the under side of the sleeve *b*, and in the slot of said head 65 is pivoted a block *d*² on a transverse pin *d*', so as to have a limited swinging motion. The block *d*² has a bore for the reception of the tool *e*, which latter is clamped in the block by means of a clamping-bolt *d*³, that works in a 70 threaded opening of said block, or preferably by means of such a bolt and a washer interposed between it and the tool, as clearly shown in Fig. 4. To prevent its falling out, the sleeve *d* is secured by two screw-bolts *f*, which 75 pass through it and which are screwed into suitable slide-pieces *f'* *f*', preferably of T shape, situated in a groove of the socket *b*. The opening of the socket *b* is somewhat larger in the direction of the feed movement, (see 80 Fig. 3,) so as to allow of a parallel movement being imparted to the sleeve *d* in the socket *b* during the working of the machine, and therefore to the tool itself a movement differential with respect to the feed motion. This 85 movement can be effected by suitable means—for instance, by an endless screw *g*, fixed in the socket *b*, which engages suitable teeth cut in the sleeve *d*, Fig. 4. To facilitate access to the adjusting-screw *g*, the casing *a* is provided with two suitable recesses or gaps *a*⁴.

The adjustability of the tool above described in the reversible socket during the working of the machine is of great importance, as it is possible only by this to obtain 95 in the forward as well as in the backward movement of the work a uniform cut as well as to take off an equally thick shaving, as the tool can never be so exactly sharpened and set that it will always cut uniformly even after being turned through one hundred and 100 eighty degrees.

The movement or reversal of the tool—that is to say, of the socket carrying the said tool and its sleeve—to the extent of one hundred and eighty degrees for allowing the forward or backward movement of the work *W*, Fig. 1, which movement takes place at the end or during the change of stroke of the table *T*, is effected in the following manner: A toothed segment *i*, adapted to be rotated on the axis *h*, secured to the casing *a*, engages with the toothed wheel *b* and turns the said wheel, and with it the tool *e e'*, through an angle of one hundred and eighty degrees at every movement from the one end position, Fig. 2, to the other, Fig. 3, and vice versa. The segment *i* is turned by a rope-pulley *k*, connected with it, which pulley is turned in one or other direction by two ropes *m* and *m'*, conducted over suitable guide-rollers *l* and weighted with a weight *l'*. The alternate tightening and loosening of the two ropes *m* and *m'* is effected simultaneously at the end of each stroke by the belt-fork *p*, which shifts the belts *n* and *n'* from the loose pulleys *o* to the fixed pulley *o'*, to which fork the free ends of the ropes are fixed at *p'*. The shifting of the belt-fork *p* is effected by a horizontal rod *g*, which is worked in well-known manner by suitable levers or even by hand.

The coupling of the segment *i* and the rope-pulley *k* has in both directions a certain lost motion, which serves to turn the lever *c* by means of a suitable cam *k'* and to release thereby the spring-bolt *c* to set free the socket *b*. After the rotation or reversing of the socket *b* or at the end of the turning motion of the rope-pulley *k* and the segment *i*, respectively, the spring-bolt *c* springs again into the groove *b* opposite to it, so as to hold the socket during the cutting operation.

Having fully described my said invention, what I claim, and desire to secure by Letters Patent, is—

- 45 1. In a metal-planer, the combination with the planer-head, a support for the tool-holder carried by said head, a tool-holder journaled in said support to revolve about its vertical axis, and mechanism adapted to impart to said tool-holder a semirotary motion, of adjusting devices for adjusting the tool-holder within its support in a direction at right angles to the direction of motion of the work, for the purpose set forth.
- 55 2. In a metal-planer, the combination with the planer-head, a support for the tool-holder secured thereto, and the tool-holder journaled in said support; of the planer-head driving-shaft, mechanism for changing the direction of rotation of said shaft, and appliances operated by said mechanism for imparting a semirotation to the tool-holder, for the purpose set forth.
- 65 3. In a metal-planer, the combination with the planer-head, a support for the tool-holder secured thereto, a tool-holder journaled in said support, gearing adapted to impart ro-

tary motion to the tool-holder, a locking-bolt for locking said holder against rotation, and a spring operating to hold said bolt in engagement with the holder; of mechanism operating automatically and adapted to periodically move the aforesaid locking-bolt out of engagement with the holder, impart to the latter a semirotary movement in one or the other direction and then release the bolt, for the purpose set forth.

4. The combination with the tool-holder support, *a*, the socket *b*, and the endless screw *g* journaled in said socket; of the tool-holder *d*, having lateral motion in socket *b* and being geared to the aforesaid screw *g* for the purpose set forth.

5. The combination with the planer-head, a support for the tool-holder secured thereto, the socket *b* journaled in said support and having its lower end enlarged and abutting against the like end of its support, the tool-holder journaled in said socket and having its lower end enlarged and abutting against the like end of said socket, of the block *d* for the reception of the tool pivoted in said enlarged end of the tool-holder, and means for clamping the tool to said block, for the purpose set forth.

6. The combination with the planer-head, a support for the tool connected therewith to swing on a horizontal pivot, the socket *b* journaled in said support and held against end-wise motion therein; of the tool-holder journaled in said socket and having lateral motion therein, said holder having an enlarged vertically-slotted lower end or head, a block for the reception of the tool pivoted in the slot in said head and means for clamping the tool to said block, for the purposes specified.

7. The combination with the planer-head, a support for the tool-holder secured thereto, the socket *b* journaled in said support and provided with two lock-notches *b* diametrically opposite each other and carrying a bevel-wheel *b* at its upper end, the sleeve *d* connected with said socket, a spring-actuated bolt adapted to engage one or the other of the notches *b*, and the sleeve *c* fulcrumed to the aforesaid support; of the toothed segment *i* in gear with the bevel-wheel *b* and revoluble on a spindle secured to the tool-holder support, the cam *k'* and rope-pulley *k* revoluble on said spindle with the segment-gear, said cam adapted to rock the aforesaid lever *c*, the ropes or cords *m* and *m'* having one end secured to said rope-pulley, and suitable guide-pulleys whereby an oscillating motion in one or the other direction is imparted to the segment-gear and cam *k'*, substantially as and for the purpose set forth.

8. The combination with the spindle *h*, toothed segment *i*, rope-pulley *k*, cam *k'*, the parts actuated thereby and the ropes *m* and *m'* having one end secured to said rope-pulley; of the planer-bed-driving shaft, its loose and fast belt-pulleys *o*, *o'*, the driving-belt and the belt-shifting forks *p* to which the upper ends

of said ropes are secured, and suitable guide-pulleys for said ropes, substantially as and for the purpose set forth.

9. The combination with the planer-head, 5 a tool-holder support connected therewith to revolve about a horizontal pivot a' , means for locking said support against rotation, the socket b journaled in said support to revolve about its vertical axis, and the endless screw g journaled in said socket; of the sleeve d having lateral motion in the aforesaid sleeve

and geared at its upper end to said screw g , the block d^2 arranged to swing on a horizontal pivot d' at right angles to pivot a' within a recess in the head of sleeve d , and the 15 clamping screw-bolt d^3 , substantially as and for the purpose set forth.
